UNITED STATES PATENT OFFICE.

JACOB W. MOSER, OF BYERS, TEXAS.

CORK-PULLER.

1,281,631.

Specification of Letters Patent. Patented Oct. 15, 1918.

Application filed March 25, 1918. Serial No. 224,562.

To all whom it may concern:

Be it known that I, JACOB W. MOSER, a citizen of the United States, residing at Byers, in the county of Clay, State of Texas, 5 have invented certain new and useful Improvements in Cork-Pullers; and I do hereby declare the following to be a full clear, and exact description of the invention, such as will enable others skilled in the art to 10 which it appertains to make and use the same.

The invention relates to cork extractors, and more particularly to the class of cork pullers.

15 The primary object of the invention is the provision of a device of this character, wherein a cork when engaged in the neck of a bottle can be readily gripped for the pulling of the same therefrom, without damaging the bottle or breaking the cork.

20 Another object of the invention is the provision of a device of this character, wherein the construction thereof is novel in form so that a cork can be withdrawn from the 25 mouth of a bottle, one of the blades or jaws of the device being slidable so that it may be inserted between the cork and the mouth of the bottle for the firm gripping of the cork to enable the extracting thereof with des- 30 patch.

35 A further object of the invention is the provision of a device of this character, which is extremely simple in construction, readily and easily operated, strong, durable, thoroughly reliable and efficient in its purpose, and inexpensive to manufacture.

With these and other objects in view the invention consists in the features of construction, combination and arrangement of 40 parts, as will be hereinafter fully described, illustrated in the accompanying drawing, and pointed out in the claims hereunto appended.

In the accompanying drawing, Figure 1 45 is a side elevation of the device constructed in accordance with the invention;

Fig. 2 is an edge elevation thereof;

Fig. 3 is an enlarged sectional view on the line 3—3 of Fig. 1;

50 Fig. 4 is an enlarged sectional view on the line 4—4 of Fig. 1;

Fig. 5 is a fragmentary sectional elevation similar to Fig. 1 looking toward the opposite side of the device.

55 Similar reference characters indicate cor-

responding parts throughout the several views in the drawing.

Referring to the drawing in detail, the cork extractor or puller comprises a main or body plate 5 preferably of a shape constituting a long arm 6 and a relatively short arm 7 at right angles thereto, the latter being formed with a guide 8 in which is slidably fitted the shank 9 of a handle 10 integral therewith, the shank being preferably of squared formation in cross section.

Opposite the handle 10 is a companion swinging handle 11 supported upon a pivot 12 mounted in the long arm 6 of the plate 5 and the inner end of this handle 11 has 70 knuckle joint or hinge connection as at 13 with a swinging shank 14 supported upon a pivot 15 mounted in the plate 5 opposite the sliding shank 9 for a purpose presently described.

75 Formed on the outer ends of the shanks 9 and 14 are outwardly curved blades constituting jaws 16 which are opposite each other and are formed with outwardly tapered pointed ends 17, the jaws being adapted for insertion within the mouth of a bottle between the wall of said mouth and a cork and on compressing the handles 10 and 11 toward each other the swinging jaw 16 will approach the slidable jaw 16 for the positive gripping of the cork therebetween so that it can be withdrawn or extracted from the mouth of the bottle without possibility of the cork slipping from between the jaws during the operation of extracting the said 90 cork from the bottle.

80 The shank 9 of the handle 10 being slidably mounted in the guide 8 will permit the jaw 16 of said shank to be readily inserted between the mouth of the bottle and the cork 95 therein to a point beneath the cork to insure a firm gripping of the latter by both jaws 16 of the device when the cork is to be withdrawn from the mouth of the bottle.

From the foregoing it is thought that the 100 construction and manner of operation of the device will be clearly understood and therefore a more extended explanation has been omitted.

What is claimed is:

105 1. A device of the character described comprising slidable and pivoted jaws mounted opposite and in spaced relation to each other to directly engage a cork at diametrically opposite points thereof, and handles con- 110

nected with the jaws for operating the same, one of the handles being designed to move the pivot jaw toward and away from the slideable jaw without disturbing said slideable jaw.

2. A cork puller of the character described comprising a main plate, a guide on said plate, a slideable shank fitted in said guide and having a handle, a swinging handle pivoted to the plate opposite the first named handle, a swinging shank pivoted to the plate and connected with the swinging handle, and jaws carried by said shanks.

3. A cork puller of the character described comprising a main plate, a guide on said

plate, a slideable shank fitted in said guide and having a handle, a swinging handle pivoted to the plate opposite the first named handle, a swinging shank pivoted to the plate and connected with the swinging handle, and jaws carried by said shanks, the jaws being of outwardly curved formation in cross section and having tapered pointed free ends.

In testimony whereof, I affix my signature, ²⁵ in the presence of two witnesses.

JACOB W. MOSER.
